ARTHUR E. LYONS, OF LANSING, MICHIGAN

DESIGN FOR A COMBINED DISPLAY-STAND BASE AND STANDARD

Application filed February 20, 1931. Serial No. 38,745. Term of patent 3½ years.

To all whom it may concern:

Be it known that I, ARTHUR E. LYONS, a citizen of the United States, residing at Lansing, in the county of Ingham and State of Michigan, have invented a new, original, and ornamental Design for Combined Display-Stand Base and Standard, of which the following is a specification, reference being had to the accompanying drawing forming part thereof.

In these drawings:

Figure 1 is a side elevation of a combined display stand base and standard, showing my new design, and

Figure 2 is a top plan view thereof.

I claim:

The ornamental design for a combined display stand base and standard, as shown.

ARTHUR E. LYONS.
